(57) **CLAIM**

We claim the ornamental design for a private access gown, as shown and described.

DESCRIPTION

FIG. 1 is a front view showing my new design, with portions of a front panel of the gown shown folded over to show portions of a rear panel of the gown;

FIG. 2 is a front view thereof;

FIG. 3 is a rear view thereof.

FIG. 4 is a right side view thereof;

FIG. 5 is a left side view thereof;

FIG. 6 is a top view thereof; and,

FIG. 7 is a bottom view thereof.

The broken lines in the drawings illustrate environmental structure and form no part of the claimed design.
